CLAIM

The ornamental design for a sink with vessel rinser, as shown and described.

DESCRIPTION

FIG. 1 is an elevated front perspective view of a sink with vessel rinser showing the new design in an overmount embodiment;

FIG. 2 is a top plan view of the sink with vessel rinser of FIG. 1;

FIG. 3 is a cross-sectional front view of the sink with vessel rinser of FIG. 1, looking rearwards;

FIG. 4 is a first cross-sectional side view of the sink with vessel rinser of FIG. 1, sectioned across the sink and looking right;

FIG. 5 is a second cross-sectional side view of the sink with vessel rinser of FIG. 1, sectioned across the vessel rinser and looking right;

FIG. 6 is a bottom plan view of the sink with vessel rinser of FIG. 1;

FIG. 7 is a rear elevation view of the sink with vessel rinser of FIG. 1; the front elevation view being substantially a mirror image;

FIG. 8 is a left elevation view of the sink with vessel rinser of FIG. 1; and

FIG. 9 is a right elevation view of the sink with vessel rinser of FIG. 1.

FIG. 10 is an elevated front perspective view of a sink with vessel rinser showing the new design in an overmount embodiment;

FIG. 11 is a top plan view of the sink with vessel rinser of FIG. 10;

FIG. 12 is a cross-sectional front view of the sink with vessel rinser of FIG. 10, looking rearwards;

FIG. 13 is a first cross-sectional side view of the sink with vessel rinser of FIG. 10, sectioned across the sink and looking right;

FIG. 14 is a second cross-sectional side view of the sink with vessel rinser of FIG. 10, sectioned across the vessel rinser and looking right;

(Continued)

FIG. 15 is a bottom plan view of the sink with vessel rinser of FIG. 10;

FIG. 16 is a rear elevation view of the sink with vessel rinser of FIG. 10; the front elevation view being substantially a mirror image thereof;

FIG. 17 is a left elevation view of the sink with vessel rinser of FIG. 10; and,

FIG. 18 is a right elevation view of the sink with vessel rinser of FIG. 10.

The broken lines are for illustrative purposes only and form no part of the claimed design.

The dash-dash lines are for illustrative purposes only and form no part of the claimed design. The dash-long dash lines show a boundary between a portion of the sink forming part of the claimed design and a portion of the sink forming no part of the claimed design.
